METHOD OF MAKING MOTOR FUEL

Joseph Hidy James, Pittsburgh, Pa., assignor to
Clarence P. Byrnes, Pittsburgh, Pa., as trusteeNo Drawing. Application June 5, 1941,
Serial No. 396,753

5 Claims. (Cl. 196—49)

One of the main drawbacks of the several present methods of catalytically cracking mineral oil or fractions thereof is that after once carrying out such step and fractionating the product to recover the portion within the gasoline range, the large remainder cannot be recycled with profit. The motor fuel recovery from repeating the cracking is too small to be commercially practicable and such remainder must be turned into the catch-all of fuel oil or some cheap product.

I have discovered that such remainder from catalytic cracking can be partially oxidized, preferably by my well known vapor-phase catalytic process; and that if the oxidized product be then cracked by either thermal or catalytic cracking, fractionating of the cracked product will give a sufficient and satisfactory yield within the gasoline or motor fuel range. I can thus largely increase the percentage of the desired product within the gasoline or motor spirit range, and in some cases nearly double the recovery.

In carrying out my process, the crude oil or a fraction may be cracked in the presence of a catalyst by any of the now well known processes, such as the Houdry, the aluminum chloride, or others, and the product fractionated to recover the portion within the gasoline range. The remainder or such portion as it is desired to recycle for cracking is then treated to partially oxidize it, producing a series of oxygen derivatives in the range from alcohols to oxy-acids. For such step I prefer to use my well known catalytic vapor-phase partial-oxidation method wherein such portion is vaporized, mixed with air or an oxygen containing gas and passed through a hot reaction zone preferably in contact with a catalyst such as molybdenum, vanadium, or uranium oxides or compounds. Such process is set forth in a number of my patents such as Reissue No. 18,552; No. 2,085,221; and No. 2,054,571; and preferably with multiple catalytic contacts and air admissions as in the last mentioned patent. The exit stream from this partial oxidation system may be condensed and the condensate cracked either thermally or catalytically; or such exit stream may be cracked in vapor phase by passing it through a cracking apparatus of either thermal or catalytic type. If condensed, the condensate may if desired be treated to remove acids, as for example, by saponification or neutralization. After acid removal, the product or a distilled fraction thereof may then be cracked thermally or catalytically.

The advantages of my invention result from

the large increase in the recovery of the fractions within the gasoline or motor spirit range. The partial oxidation step is exothermic and of low cost and acts to "sensitize" or prepare the remainder so that recycling through a cracking step will greatly increase the recovery of the desired fraction.

The partial oxidation may be carried out in the liquid phase; the cracking may be carried out in the liquid or vapor phase or both; cracking catalysts in recracking may be used or not as desired, and if used, different catalytic processes may be used in the original cracking step; and many other changes may be made without departing from my invention.

I claim:

1. In the process of making motor fuel of gasoline type from mineral oil, the steps comprising cracking a portion of mineral oil to convert a part thereof into gasoline-type motor-fuel, fractioning the product to separate out the lighter gasoline portion, then partially-oxidizing a heavier fraction under conditions which form a material percentage of oxygen derivatives of hydrocarbons in the range from alcohols to oxy-acids, and recracking said partially-oxidized heavier fraction containing said oxygen derivatives of hydrocarbons to produce further amounts of gasoline-type motor fuel.
2. In the process of making motor fuel of gasoline type from mineral oil, the steps comprising catalytically cracking a portion of mineral oil to convert a part thereof into gasoline-type motor-fuel, fractioning the product to separate out the lighter gasoline portion, then partially-oxidizing a heavier fraction under conditions which form a material percentage of oxygen derivatives of hydrocarbons in the range from alcohols to oxy-acids, and recracking said partially-oxidized heavier fraction containing said oxygen derivatives of hydrocarbons to produce further amounts of gasoline-type motor fuel.
3. In the process of making motor fuel of gasoline type from mineral oil, the steps comprising cracking a portion of mineral oil to convert a part thereof into gasoline-type motor fuel, fractioning the product to separate out the lighter gasoline portion, then partially-oxidizing a heavier fraction in vapor phase under conditions which form a material percentage of oxygen derivatives of hydrocarbons in the range from alcohols to oxy-acids, and recracking said partially-oxidized heavier fraction containing said oxygen derivatives of hydrocarbons to produce further amounts of gasoline-type motor fuel.

4. In the process of making motor fuel of gasoline type from mineral oil, the steps comprising cracking a portion of mineral oil to convert a part thereof into gasoline-type motor-fuel, fractionating the product to separate out the lighter gasoline portion, then partially-oxidizing a heavier fraction under conditions which form a material percentage of oxygen derivatives of hydrocarbons in the range from alcohols to oxy-acids, removing any acids therefrom, and then re-cracking the partially oxidized portion containing oxygen derivatives other than acids to produce further amounts of gasoline-type motor fuel.

5. In the process of making motor fuel of gasoline type from mineral oil, the steps comprising cracking a portion of mineral oil to convert a part thereof into gasoline-type motor fuel, fractionating the product to separate out the lighter gasoline portion, then partially-oxidizing a heavier fraction under conditions which form a material percentage of oxygen derivatives of hydrocarbons in the range from alcohols to oxy-acids, and re-cracking said partially oxidized heavier fraction in vapor phase to produce further amounts of gasoline-type motor fuel.

JOSEPH HIDY JAMES.
